(57) **CLAIM**

The ornamental design for a waffle iron, as shown and described.

DESCRIPTION

FIG. 1 is a front and left-side perspective view of a waffle iron embodying my new design, shown in an open configuration;
FIG. 2 is a left-side elevational thereof, the right-side elevational view being a mirror image;
FIG. 3 is a rear elevational view thereof;
FIG. 4 is a front elevational view thereof;
FIG. 5 is a top plan view thereof;
FIG. 6 is a bottom plan view thereof;
FIG. 7 is a front and left-side perspective view of the waffle iron of FIGS. 1-6, illustrated in the closed position;
FIG. 8 is a front and left-side perspective view of the waffle iron of FIGS. 1-7, wherein the halves pivot on a lateral side rather than an end;
FIG. 9 is a front and left-side perspective view of an alternative form of the waffle iron embodying my new design, shown in an open configuration;
FIG. 10 is a left-side elevational view of the waffle iron of FIG. 8, the right-side elevational view being a mirror image;
FIG. 11 is a rear elevational view thereof;
FIG. 12 is a front elevational view thereof;
FIG. 13 is a bottom plan view thereof;
FIG. 14 is a top plan view thereof;
FIG. 15 is a top and left-side perspective view of the waffle iron of FIGS. 9-14, shown in a closed configuration; and,
FIG. 16 is a front and left-side perspective view of the waffle iron of FIGS. 9-15, wherein the halves pivot on a lateral side rather than an end.
